[57] CLAIM

The ornamental design for a landscape timber connecting system member, as shown and described.

DESCRIPTION

FIG. 1 is a front perspective view of a landscape timber connecting system member embodying our new design, taken from above and the right, the broken line showing of a second member is for illustrative purposes only and forms no part of the claimed design;

FIG. 2 is a front perspective view thereof;

FIG. 3 is a perspective rear view thereof;

FIG. 4 is a rear elevational view thereof;

FIG. 5 is a top plan view thereof, the bottom plan view being a mirror image;

FIG. 6 is a left side elevational view thereof;

FIG. 7 is a front elevational view thereof; and,

FIG. 8 is a right side elevational view thereof.
